ATTORNEY

UNITED STATES PATENT OFFICE

EDWARD McNAMARA, OF WOLSEY, SOUTH DAKOTA

CALENDAR

Application filed January 23, 1930. Serial No. 422,860.

This invention relates to certain new and useful improvements in calendars of the perpetual type.

An object of the invention contemplates the provision and arrangement of a housing including a sight opening through which the abbreviations of the months of the year are exhibited.

An additional object of the invention consists in the provision of a pocket for numeral carrying members interchangeably arranged to correspond numerically with the days of the week.

An additional object of the invention embodies a retaining element upon the housing to prevent displacement of the numeral carrying members.

More specifically stated the face of the housing is provided with means upon the face thereof bearing the abbreviations of the days of the week.

With the above and other objects in view, the invention further consists of the following novel features and details of construction, to be hereinafter more fully described, illustrated in the accompanying drawing and pointed out in the appended claim.

In the drawing:—

Figure 1 is a front elevation of my improved form of perpetual calendar.

Figure 2 is a vertical sectional view taken on line 2—2 of Figure 1.

Figure 3 is a horizontal sectional view taken through the pocket portion and illustrating the arrangement of the numeral carrying members therein.

Referring to the drawing in detail where in like characters of reference denote corresponding parts, the reference character 10 indicates generally a form of housing which may be of hollow or solid construction, may be designed to sit upright upon a desk or other surface and in the present application of the invention I employ an apertured tab or ear, such as indicated at 11, to adequately secure a housing upon a wall surface and the like subsequent to the passage of a fastening element through the aperture.

As mentioned in the foregoing, the housing is provided with a sight opening and same

is identified by the reference numeral 12. The tab or ear 11 extends or otherwise depends for an appreciable distance back of the housing to form the rear wall of a slot or passage 13 having communication at its ends with the upper edge of the housing and the sight opening 12. Placards 14, preferably three in number, each of which having the abbreviations of two of the different months of the year upon both sides thereof are arranged inversely whereby each of the abbreviations will be effectively exposed in readable form through the sight opening 12 in the manner suggested in Figure 1 of the drawing.

The pocket portion, referred to in the foregoing and as indicated at 15 of elongated formation extending horizontally with the face of the housing is disposed an appreciable distance below the sight opening 12. The outer face of the housing 10, however, is provided with an elongated strip 16 arranged immediately above the upper edge of the pocket 15 and subdivided into blocks or subdivisions 17, preferably seven in number and which are to separately contain the abbreviations of the days of the week. Strips members 18, of elongated and flat formation, measure lengthwise thereof for appreciable distances greater than that of the width of the pocket 15 and in the application of the strips, it is necessary to gouge out or otherwise provide under-cut grooves 19 within the upper edges of the pocket 15 to facilitate the insertion of the strip members. By such connection the upper ends of the strip members will be effectively held against accidental displacement.

The flat sides of the strip members 18 are provided with spaced vertical series of numerals indicative of the day dates of the months; each of which having different series of numerals and may be interchangeably arranged to exhibit the day dates for a month in advance. The opposed side walls of the pocket 15 are provided with a horizontally projecting pocket 20 and an inwardly and downwardly inclined slot 21 respectively, both of which being disposed adjacent the lower edge of said pocket. A bar member or retaining element, such as indicated at 22, having one end disposed within the horizon-

tally disposed pocket 20 and the other end slidably mounted within the slot 21 is tensioned throughout the major portion of its length against the outer surfaces of the strip members 18 whereby the latter will be maintained upon their inner sides or faces flush against the bottom wall of the pocket 15 and from which positions same may not become accidentally displaced.

- 10 It is to be noted that in the present form of calendar there will be no leaflets or pages to tear off daily, consequently the usual disturbance caused by the rustling or flapping of such leaflets and the obscurity thereof incident to curling upwardly from the lower edges thereof is overcome. In the perpetual calendar it is only necessary to set up or reset same at the end of a month for the term of the ensuing month.
- 15 20 The invention is susceptible of various changes in its form, proportions and minor details of construction, and the right is herein reserved to make such changes as properly fall within the scope of the appended claim.
- 25 Having described the invention, what is claimed is:—

A perpetual calendar comprising a housing including a vertical passage within its upper portion in communication with an elongated horizontally disposed sight opening exposed toward the front, placards removably secured within said passage having the abbreviations of the months of the year inversely arranged adjacent the opposed side edges and upon both sides to selectively exhibit the abbreviations of the months through the sight opening in readable formation, said housing being further provided with a pocket recessed for an appreciable distance in the face thereof and below the sight opening, the upper edge of said pocket having an undercut groove, strip members receivable within said pocket and projecting at their uppermost ends within the under-cut groove are provided with successions of day date legends upon opposite sides thereof, means carried upon that portion of the face of the housing overhanging the under-cut groove including the days of the week identifying the day dates, said housing having oppositely disposed horizontally aligned pockets within the side edges of the first mentioned pocket, one of the pockets being downwardly and inwardly projected from and opening to the front, and a bar removably positioned within the pockets and engaging the strip members to prevent accidental displacement thereof.

In testimony whereof I affix my signature.

EDWARD McNAMARA.
